UNITED STATES PATENT OFFICE.

GUSTON A. SHELTON, OF RUSSELLVILLE, KENTUCKY.

CAR-COUPING.

SPECIFICATION forming part of Letters Patent No. 548,666, dated October 29, 1895.

Application filed May 23, 1895. Serial No. 550,407. (No model.)

To all whom it may concern:

Be it known that I, GUSTON A. SHELTON, a citizen of the United States, residing at Russellville, in the county of Logan and State of Kentucky, have invented a new and useful 5 Car-Coupling, of which the following is a specification.

The invention relates to improvements in car-couplings.

10 The object of the present invention is to improve the construction of car-couplings, and to provide a simple, inexpensive, and efficient one capable of coupling automatically and of being readily uncoupled from the 15 top or sides of a car, and adapted to be connected with the ordinary construction of draw-head of the pin-and-link form.

The invention consists in the construction and novel combination and arrangement of 20 parts hereinafter fully described, illustrated in the accompanying drawings, and pointed out in the claims hereto appended.

In the drawings, Figure 1 is a perspective view of a car-coupling constructed in accordance with this invention and shown applied to a car. Fig. 2 is a longitudinal sectional view of two draw-heads coupled. Fig. 3 is a detail perspective view of the link lifting and guiding frame.

25 Like numerals of reference indicate corresponding parts in all the figures of the drawings.

1 designates a draw-head mounted on a car 2 in the usual manner, and provided at its 30 top with a pair of recesses or pockets 3 and 4, extending longitudinally of the draw-head and open at the front thereof. The recess or pocket 3 has pivoted in it by a transverse pin 5 an arrow-headed link 6, which is supported 35 normally in a horizontal position by the bottom of the recess or pocket 3, and the other recess or pocket 4 has a flaring mouth and a contracted neck, and is provided in rear of the same with an enlargement.

40 The head 7 of the link is arrow-shaped and is rounded and beveled at its lower face and is adapted to slide up the flared portion of the pocket or recess 4 and to drop into the enlargement thereof. The shank or bar of the 45 link fits snugly between the sides or walls of the recess or pocket 4, and the shoulders formed by the head of the link engage those

formed by the enlargement of the recess or pocket 4. The flared portion of the recess or pocket 4 permits the necessary movement of 55 the draw-head in rounding curves and prevents any strain on the draw-head resulting from the same being cramped when a train is passing around a curve.

The head of the link is retained in the enlargement of the recess or pocket 4 against any accidental displacement resulting from the jars and sudden jerks incident to the passage of a train by a hinged weighted cover 9, located at the top of the enlargement of the 65 recess or pocket, and provided at its back or inner end with a flange 10 to limit its upward swinging to prevent it from being thrown rearward too far, and to cause it to drop automatically in position after being lifted by 70 a link.

The link is guided into the recess or pocket of a draw-head, should one draw-head be at a greater elevation than the other, by a link-lifting frame 11, which operates principally 75 to disengage the links to effect the operation of uncoupling. The link-lifting frame is constructed of metal, and consists of a substantially U-shaped front portion 12, embracing the sides of the draw-head and provided at 80 its lower end with an angular bend, and having its front transverse portion resting upon a shoulder 13 of the draw-head, and thereby protected from injury and prevented from being mashed when two draw-heads come together for coupling.

85 The link-lifting frame is provided at the top of the sides of the U-shaped portion with upward-extending arms 14 and rearwardly-extending arms 15. The upward-extending 90 arms are connected by a cross-piece 16 and the rearwardly-extending arms are pivoted to the draw-head. The transverse bar or cross-piece 16 is provided with a central loop and is arranged in eyes of the upwardly-extending 95 arms 14, and its central loop is loosely engaged by a loop-shaped arm 18 of a transverse rock-shaft 19. The rock-shaft 19 is journaled in suitable bearings of the car and is provided at its ends with handles located at the 100 sides of the car, and when its forwardly-extending arm 18 is swung upward it carries with it the link-lifting frame. The forwardly-extending arm 18 is connected by a chain

20 with a rod 21, which extends to the top of the car to enable the operation of coupling to be performed from that point. The arm 18 consists of a bend, and its loose connection 5 with the pivoted link-lifting frame permits the necessary longitudinal movement of the draw-head, and the chain also accommodates itself to such movement. When it is adapted to maintain the link in an elevated position to prevent the operation of coupling, the arm 18 is maintained in a raised position by being engaged by a ring 22, connected by a link 23 with the car.

15 The draw-head is provided below the pair of pockets with a link opening or cavity 24, adapted to receive the ordinary construction of link, which is designed to be engaged by a coupling-pin passing through a coupling-pin perforation 25, offset from the pocket 3, to enable a coupling-pin to be placed in it without interfering with the arrow-headed link 6.

20 It will be seen that the car-coupling is exceedingly simple and inexpensive in construction, that it is positive and reliable in operation, and that when two draw-heads come together their links will automatically engage the recesses or pockets and effect the 25 operation of coupling. It will also be apparent that the operation of uncoupling may be readily performed from the top and sides of a car, to avoid the necessity of going between cars.

30 Changes in the form, proportion, and the minor details of construction may be resorted to without departing from the principle or sacrificing any of the advantages of this invention.

What I claim is—

1. In a car-coupling, the combination of a draw-head, a link, a pivoted link lifting frame, 40 comprising a substantially U-shaped portion arranged on the sides of the draw-head and extending across the front of the same beneath the link, the rearwardly extending arms pivoted to the sides of the draw-head, and the 45 upwardly extending arms, a transverse bar connecting the upwardly extending arms, and a rock-shaft, provided with a loop-shaped arm 18 receiving the transverse bar, and adapted to raise and lower the link lifting frame, substantially as described.

2. In a car coupling, the combination of a draw-head provided at its top with a pair of pockets, and having at its front a supporting shoulder, a link pivotally mounted in one of 50 the pockets and arranged to swing upward, a link lifting frame, comprising a U-shaped portion extending around the front of the draw-head, and resting upon the shoulder thereof, and located at opposite sides of the 55 draw-head, rearwardly extending arms pivoted to the draw-head, the upwardly-extending arms and a transverse bar connecting the upwardly-extending arms, and an operating mechanism connected with the transverse bar, 60 substantially as described.

In testimony that I claim the foregoing as my own I have hereto affixed my signature in the presence of two witnesses.

GUSTON A. SHELTON.
